(57) **CLAIM**

The ornamental design for an exfoliating hand cloth, as shown and described.

DESCRIPTION

FIG. 1 is a front perspective view of an exfoliating hand cloth showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The stippling or wavy lines in the drawings each represent a contrast in appearance or texture compared to other portions of the design.

1 Claim, 5 Drawing Sheets
